UNITED STATES PATENT OFFICE.

THOR RAJE, OF LOS ANGELES, CALIFORNIA.

TALKING-MACHINE.

1,378,133.

Specification of Letters Patent. Patented May 17, 1921.

Application filed August 17, 1916. Serial No. 115,402.

To all whom it may concern:

Be it known that I, THOR RAJE, a citizen of the United States, residing at Los Angeles, in the county of Los Angeles and State 5 of California, have invented new and useful Improvements in Talking - Machines, of which the following is a specification.

My invention relates to talking machines and the primary object thereof is to provide 10 a multiple record machine arranged to play records of substantially large diameter and to support a plurality of such records in position for successive use.

Another object is to provide a multiple 15 record talking machine arranged to support a plurality of large annular records in operative position without substantially increasing the size of the machine over the sizes of machines in general use with other types 20 of records.

A further object of this invention is to provide a machine capable of playing a series of records selectively, one at a time, in successive order and capable further, of 25 repeating a selected record at the option of the operator.

A further object is to provide means for rendering lengthy musical composition which cannot usually be rendered on other 30 types of machines.

In talking machines of known construction it has been found impossible to completely record certain lengthy musical compositions owing to the fact that records of 35 sufficient size cannot be made with practicability. Such compositions have therefore been revised and changed to adapt them for reproduction on talking machines, and for this reason the value of the record, especially 40 to students of music, has been greatly depreciated. To overcome this objection, the present invention has been designed and contemplates preferably the provision of a plurality of records of novel construction 45 mounted upon a mandrel in such a manner as to permit of the reproduction of each record in succession whereby any musical composition may be played in its entirety.

The invention further contemplates the 50 utilization and saving of space by providing a mandrel of hollow construction to enable the mounting of the driving means, including a motor therein and means for removing the mandrel from the casing. This construction permits the use of a motor of relatively large capacity. By this construction

the mandrels may be employed as files or holders for records while not being used. Due to the relatively great diameter and size of the mandrels, they also act as a fly wheel 60 for the motor.

Another object is the provision of a motor which may be used to operate any mandrel selected. To this end a motor housed in a suitable casing is arranged to be detachably 65 secured within a mandrel.

A further object is to provide a means for identifying the record mounted upon the mandrel, and to this end a suitable index is carried by the machine cabinet and has associated therewith an index finger extending from the sound box carrying lever so that the latter may with facility be adjusted to a position to play any desired record of the series 70 mounted upon the mandrel.

A still further object is the provision of an adjustable automatic repeat device of novel construction carried by the cabinet and arranged in the path of movement of the sound box carrying lever and actuated by 80 contact therewith, to lift the sound box from engagement with the record groove, return the same the width of the record just played and then lower said sound box into contact with said record.

Figure 1 is a vertical longitudinal sectional view taken through the talking machine cabinet.

Fig. 2 is a fragmentary detail section of the frame on the line 2—2 of Fig. 1.

Fig. 2^a is a detail view of the frame in the plane of Fig. 2.

Fig. 3 is a fragmentary longitudinal section of the mandrel with a plurality of records thereon.

Fig. 4 is a fragmentary section on the line 4—4 of Fig. 1.

Fig. 5 is a fragmentary top view showing the means for identifying the several records mounted upon the mandrel.

Fig. 6 is a fragmentary side elevation of the automatic repeating device employed in connection with the invention.

Fig. 7 is a view similar to Fig. 6 showing the repeating device in position after the sound box carrying lever has been returned to the beginning of the record.

Fig. 8 is a section on the line 8—8 of Fig. 6, showing the repeating device in the position just previous to the contact of the sound box carrying lever therewith.

Fig. 9 is a view similar to Fig. 8, but

showing the position of the parts during the return movement of the sound box carrying lever.

Fig. 10 is a detail perspective view of a contact member which forms a portion of the repeating device.

Fig. 11 is a longitudinal section through said contact member.

The invention is illustrated in what is now believed to be the preferred form, wherein the machine comprises a cabinet 12 generally of ordinary construction and having suitably mounted therein a relatively large mandrel 13 preferably of hollow construction. This mandrel is made hollow in order to economize space, and has detachably mounted in one end thereof the usual spring motor which is conventionally illustrated at 14, and is provided with a housing. A shaft 15 extends from the housing beyond the rear end of the mandrel, and is square at the end to engage a square slot in frame member 16. The slot is of bayonet form as indicated by 17 to permit insertion and removal of shaft 15. At the front end of the motor is a winding arbor 18 in alinement with shaft 15. Arbor 18 is rotatably mounted in a bayonet slot 17' in a frame member 19, and is square at the end for receiving the socket of a winding crank 20.

Suitable ratchet and pawl mechanism may be provided for winding the motor so that when operating the housing will rotate with respect to shaft 15. The specific construction of the motor is not a material part of my invention except in so far as described and may be varied in accordance with constructions well known in the motor art. The space for the motor, however, is such that a motor of large capacity and great power may be used. The motor housing has a cylindrical portion 22, is disposed in a tubular opening 24 on the end of mandrel 13 and is arranged to frictionally engage the walls thereof with the flange 23 overlaying the end wall 25 of the mandrel. This provides a construction whereby when a mandrel is removed from the cabinet the motor may be detached and inserted in another mandrel. The entire mandrel is removed by raising it so that shaft 15 is at the upper part of the bayonet slot 17 in frame 16 and arbor 18 is at the upper end of the bayonet slot 17' in frame member 19, then pulling the mandrel forward removing shaft 15 and arbor 18 from their respective slots.

Rotary movement from the mandrel 13 is transmitted by means of friction or gear teeth at the end of the mandrel to a pinion 26 carried by frame 19 interiorly of the cabinet, said pinion 26 meshing with a larger gear 27, the shaft 28 of which projects upwardly through the top of the casing and is provided at its upper end with a bevel gear 29 meshing with a similar gear

30 carried by the screw shaft 31 which extends across the top of the casing or cabinet. A guide rod 32 is also mounted upon the top of the cabinet longitudinally of the mandrel 13 in parallel relation with 31, and has mounted thereon the sound box carrying lever 33 carrying the sound box 34 at its forward end and provided adjacent its rear end with a nut 35 which meshes with the screw shaft 31 to advance the lever 33 across the top of the cabinet. The sound box 34 carries a flexible connection 36, one end of which projects into the adjacent end of the usual tone arm 37 connected at its other end by a swivel joint 37' to the sound amplifier 38 of ordinary construction, and the forward end is pivoted at 38' to sound box 34. The rear end of the lever 33 carries an index plate or strip 40 containing suitable indicia to indicate which record is being traversed by the sound box 34. Through the medium of this index any record desired may be reproduced by adjusting the lever 33 and the index finger 39 to the number of the plate 40 indicating the number of the record desired.

The mandrel 13 is preferably provided with a covering 41 of felt upon which is adapted to be mounted a plurality of records 42 of novel construction. By referring to Fig. 3, it will be seen that each of the records 42 preferably consists of a ring member or annulus whose axis or width is relatively short as compared to its circumference or diameter. Each of the records 42 as shown in Fig. 3 is of approximately the same width, but it will be understood of course that the width thereof is arbitrarily and may be regulated in accordance with the length of the composition to be reproduced. The records are all preferably tapered as indicated, and each is provided upon one edge with a flange 43 which receives therein the adjacent end of the successive record, so that when all of the records are in position on the mandrel the same are nested to permit the travel of the stylus from one record to another. The flange 43 upon its rear surface is inclined or beveled slightly so that the same will merge with the adjacent record surface of the nearest record, it being understood that the record groove is formed in the periphery or circumference of the record. It will thus be seen from the foregoing description that when the records 42 are in position on the mandrel, the sound box 34 will travel from one record onto the other and in this manner a continuous reproduction of a very lengthy composition may be obtained, and all of the records held on the mandrel may be played in series without interruption. Also, records of different pieces of music may be mounted upon the mandrel, and when it is desired to play any one of said records the lever 33

together with the sound box 34 may be adjusted as previously indicated. It will also be apparent that the mandrel may be employed in lieu of the usual record cabinet 5 for storing records when not being used, and in this way a saving of space is also accomplished.

The invention also contemplates the provision of mechanism for repeating the 10 production of any record desired, and to this end there is mounted upon the top of the cabinet forwardly of the guide rod 32 and parallel therewith, a suitable supporting rod 44 of approximately the same length 15 as the guide rod 32. Slidably mounted upon the rod 44 is a sleeve member 45 carrying at one end bevel gear 46 which is normally held out of engagement with the bevel gear 47 by means of a spring 48, the gear 47 being carried by the upper end of the shaft 49 which is driven through the medium of the gear 26. A contact element 50 is adjustable longitudinally of the sleeve 45 and secured in its adjusted position by means 20 of a cam 51 pivoted to the element, and adapted to engage said sleeve. This element 25 50 is eccentrically mounted upon the sleeve 45 so that a greater portion of the weight thereof will be on one side of the axis than on the other side and is reduced to provide 30 a surface 52 preferably in the form of a compound curve, which gives the element 50 a generally tapered formation. The length of the element 50 from the inner end of the 35 compound curve 52 to the outer extremity thereof is approximately the same as the width of a record, and when the element 50 is in normal position as shown in Figs. 6 and 10, said curve 52 is uppermost.

40 When it is desired to repeat one of the records mounted on the mandrel, the element 50 is adjusted along the sleeve 45 until the shoulder 50' formed by the inner end of the surface 52 is a slight distance in advance of the end of the particular record 45 to be repeated. The shoulder 50' of element 50 is now in position to be engaged by a pin 53 depending from lever 33. Pin 53 is provided with a lug 54 forming a shoulder 50 thereon. The shoulder on pin 53 rides on the eccentric surface of element 50 while the lug 54 bears against surface 52. As the lever 33 which carries the said pin 53 progresses farther the element 50 and sleeve 45 55 are moved along rod 44 until the bevel gear 46 is in mesh with the bevel gear 47 whereupon the sleeve 45 will be rotated and pin 53 raised. At the initial rotary movement of the element 50 the lever 33 is raised or 60 elevated by reason of its contact with the eccentric surface of element 50, and this movement of said lever will disengage the sound box 34 from the record groove. Further movement of the element 50 will 65 cause the pin and lever 33 to slide along the

edge of the surface 52, and thus return said lever 33 toward its position at the beginning of the record to be repeated. At substantially the same time that the lever 33 starts moving backward, the spring 48 will force 70 the sleeve 45 along the rod 44 and disengage the bevel gears 46 and 47 and continued rotation of the sleeve 45 will usually ensue due to the momentum given the same when the said gears initially mesh. When the 75 lever 33 and sound box 34 have reached the beginning of the record, the parts are in the position shown in Fig. 7 in full lines and owing to the mounting of the element 50 with the greater portion of its weight on 80 one side of the axis of rotation, said element will continue to rotate until the same assumes its normal position. Continued rotation of the element 50 will, owing to the formation of the reduced end, disengage 85 itself from the lever 33 and permit the sound box 34 to be lowered into contact with the record.

It will be apparent from the foregoing 90 description that the record may be repeated as many times as desired by leaving the element 50 in its adjusted position and by moving the same to the end of the sleeve 45 the records may be played in succession and without repetitions.

In order to remove and replace and change the mandrels, access is had to the interior cabinet or casing through a door 55.

It is obvious that the mounting of a plurality of records on one mandrel in my machine, obviates the necessity of continuous changes, namely, the placing and removing of each individual record before another can be played. The increased playing capacity of the motor removes the objectionable feature of continuous winding or the winding in the middle of the playing of a record. The great majority of injuries and breakages of records is due to the continuous handling in moving, removing and selection of records for placing on the machine and in proper place in the filing cabinet.

A governor 55 is operated by means of a friction roller or gear 56 which is driven by the end of the mandrel 13 in a manner 115 similar to that of the pinion 26 on the opposite end of the mandrel. This governor is preferably of the usual type and character of the ball governor and serves to regulate the speed of the mandrel 13. It is obvious that the spring motor may be wound by means of the crank 20 while the mandrel is in motion and the governor prevents excessive speed of the records during the winding operation. Rollers 57 are carried on 120 the frames 16 and 19 and contact with the lower end portions of the mandrel.

What I claim is:

1. In a machine of the character referred to, in combination, a cabinet, means for 130

supporting and revolving a phonographic element therein, a reproducer mounted to travel on said element, a sound amplifier of tapering form and curved from the upper side of said phonographic element around and under the same to the front of said cabinet, the upper portion of said sound amplifier being connected to the other portion thereof, with a swivel joint within said cabinet, said swivel portion partially encircling said phonographic element, a tubular connecting member from said reproducer and having telescopic connection with the small end of said amplifier, means for positively moving said reproducer longitudinally of said phonographic element and for turning the swivel portion of said amplifier therewith, and means for indicating different locations along said phonographic element, substantially as shown and described.

2. In a machine of the character referred to, in combination, a cabinet, a mandrel to receive a plurality of record elements thereon, means for driving said mandrel and said record elements, a reproducer, means for supporting and moving said reproducer along said record elements from one to the other throughout the series, a tone amplifier of gradually increasing diameter encircling said mandrel and said amplifier, and terminating at its large end at an opening in said cabinet, a tubular member connecting said reproducer with the small end of said sound amplifier, and having a sliding telescopic connection therewith, where-

by to permit the free bodily movement of said reproducer, without interfering with its sound transmitting connections with said sound amplifier, and an indicator moving with said reproducer and adapted to indicate the record being reproduced, substantially as described.

3. In a machine of the character referred to, in combination, a cabinet, a mandrel to receive a plurality of record elements thereon, means for driving said mandrel and said record elements, a reproducer, means for supporting and moving said reproducer along said record elements from one to the other throughout the series, a tone amplifier of gradually increasing diameter encircling said mandrel and said amplifier, and terminating at its large end at an opening in said cabinet, a part of said sound amplifier having a swivel connection with the other part thereof, a tubular member connecting said reproducer with the small end of said sound amplifier, and having a sliding telescopic connection therewith, whereby to permit the free bodily movement of said reproducer, without interfering with its sound transmitting connections with said sound amplifier, and an indicator moving with said reproducer and adapted to indicate the record being produced, substantially as described.

In witness that I claim the foregoing I have hereunto subscribed my name this 26th day of July, 1916.

THOR RAJE.
